UNITED STATES PATENT OFFICE.

ERNEST K. HOOD, OF INDIANAPOLIS, INDIANA, AND WALLACE B. WOLFF, OF CHICAGO, ILLINOIS, ASSIGNORS TO THE AMERICAN SLICING MACHINE CO., OF CHICAGO, ILLINOIS, A CORPORATION OF NEW YORK.

OPERATING MECHANISM FOR SLICING MACHINES.

1,391,320.

Specification of Letters Patent. Patented Sept. 20, 1921.

Application filed December 23, 1918. Serial No. 267,996.

To all whom it may concern:

Be it known that we, ERNEST K. HOOD and WALLACE B. WOLFF, citizens of the United States, and residing, respectively, at Indianapolis, in the county of Marion and State of Indiana, and at Chicago, in the county of Cook, in the State of Illinois, have invented certain new and useful Improvements in Operating Mechanism for Slicing Machines, of which the following is a specification.

The object of our invention is to provide a combination power and hand driven machine which can be operated conveniently and easily without disconnecting either one of the units. There are now in use a large number of hand operated slicing machines and a limited number of electrically operated machines. So far as we are aware, there are no combination units. Our arrangement is especially adapted to slicing machines such as shown in the patent issued to us June 5th, 1917, #1,228,509. It however, can be adapted to any make of machine used for slicing purposes where it is desired to drive by power or by hand.

Our invention is illustrated more or less diagrammatically in the accompanying drawings of which—

Figure 1 is a diagram showing the driving connection between the motor and slicing machine elements.

Fig. 2 is a plan of the same.

The numeral 1 represents the base of an ordinary slicing machine equipped with the standard rotary knife 2.

Mounted at some convenient place in the slicing machine is a motor 3 of any standard make.

Mounted on the outside of one of the bearings 4 of motor 3 is a gear housing 5 which contains a chain of gears and an overrunning clutch through which the motor drives the shaft 13.

Mounted on the end of shaft 13 is a sprocket wheel 19 which is connected by means of a chain 20 to a sprocket wheel 21 carried by the driving shaft 22 of a standard slicing machine. This shaft 22 is provided with a sprocket 23 which connects with a sprocket 24 by means of a chain 25 for driving the slicing machine knife 2.

Mounted on shaft 22 is a bevel gear 26 meshing with a bevel gear 27 carried by a

hand operating shaft 28 which is provided at its outer end with a hand wheel 29. All sprockets on the machine are of the same bore and interchangeable, and on account of their different diameters, any desired predetermined relative speed between the motor, hand wheel and cutting knife can be obtained by changing sprockets from one shaft to the other. The operation of the device thus far is as follows:—

If it is desired to turn the machine by hand, the hand wheel 29 is rotated in a clockwise direction. The power is transmitted through gears 27 and 26 to the machine driving shaft 22. Sprocket 23 conveys the power to chain 25 which carries it to sprocket 24 mounted on the cutting knife 2, thus driving the machine.

On account of the fact, that shaft 22 rotates sprocket wheel 21, this drives chain 20, sprocket wheel 19 and shaft 13. The overrunning clutch is so arranged on the shaft that the rotation thereof in the direction in which it is operated by the hand wheel causes it to disconnect from the motor train of gearing. This makes it possible to operate the machine by hand without making any shift or disconnection. Now if it is desired to drive the machine by the motor, the current is turned on and the power is transmitted through the chain of gears and overrunning clutch in the proper direction to transmit the power to the driving train of the slicing machine. It will thus be seen, that it is possible to operate the slicing machine by either means or by both means simultaneously and that it is not necessary to throw in or to throw out devices to disconnect either one of them. The advantages of this in a slicing machine are many.

It is very often desired to cut material until a certain weight has been reached and by operating a machine electrically, it is possible to do the cutting easily and rapidly. It might be found that there was not quite a sufficient amount of material cut to reach the desired weight when the current was snapped off and the machine stopped. It would therefore only be necessary to grasp the hand wheel and operate the machine for a short period by hand until the proper amount had been cut.

Customers often buy in small quantities and the cutting can be accomplished by

hand practically as quick as electrically. Therefore, the machine would be operated by hand under these conditions. Where large quantities of meat or other material are 5 to be cut, it is rather tiresome to operate the machine by hand, and it is therefore only necessary to snap the switch on and the machine operates electrically.

It is also of great advantage to have the 10 electric unit of any machine easily removable so that it can be repaired in case of electrical trouble. We therefore mount motor 3 on a bracket 30. This makes it possible to remove the electric unit without dis- 15 arranging any of the hand driving unit and the machine can still remain in service while electrical repairs are being made.

When the machine is driven electrically, it is advantageous to have this handle out of 20 the way and therefore by grasping it and pulling sleeve 37 out of recess 42, the handle can be swung down into the position shown in the drawings.

We claim as our invention:

25 1. A transmission mechanism comprising a motor, a reduction gear unit, unitary therewith; a power-transmitting connection

connected to said gear unit, including interchangeable gear elements and an overrunning clutch; and a hand-operated device 30 geared to the transmitting connection at a point in the connection more remote from the motor than the clutch.

2. A transmitting mechanism comprising a motor, a reduction gear unit, unitary 35 therewith; a power transmitting connection connected to said gear unit, including interchangeable gear elements; and a hand operated device geared to the transmitting connection.

3. In a slicing machine a transmission mechanism comprising a motor; a reduction gear unit, a power transmitting connection connected to said gear unit; including interchangeable gear elements; an overrunning 45 clutch and a hand operating device geared to the transmitting connection at a point in the connection more remote from the motor than the clutch.
